UNITED STATES PATENT OFFICE.

EUSEBE H. DAUDELIN, OF FALL RIVER, MASSACHUSETTS, ASSIGNOR TO HIMSELF AND
JEAN B. DAUDELIN, OF FALL RIVER, MASSACHUSETTS.

SHUTTLE.

1,078,261

Specification of Letters Patent.

Patented Nov. 11, 1913.

Application filed October 23, 1912. Serial No. 727,301.

To all whom it may concern:

Be it known that I, EUSEBE H. DAUDELIN, a citizen of the United States, residing at Fall River, county of Bristol, Commonwealth of Massachusetts, have invented certain new and useful improvements in Shuttles, of which the following is a specification.

This invention relates to hand threading shuttles and particularly to the guarding of the threading slot or passage to prevent the escape of the thread from the slot by "ballooning" or like actions during the run of the shuttle in the loom. This de-threading tendency is common to all shuttles of this type and more or less serious according to the efficiency of the thread guard located in the bushing or eye.

It is therefore, the object of my present invention to provide a simple and efficient guard capable of application to any shuttle of this general type.

The great difficulty heretofore experienced has been in avoiding interference with the threading while preventing the unthreading. For practical use the guard must not complicate or even substantially modify the established motions which the operator is accustomed to make in threading.

I accomplish my object by forming a guard shaped to overlie a portion of the threading slot and so formed as to guide the thread in such a way that although applied to the outside of the guard it will transfer itself to the inside thereof in the course of the usual motion of drawing it through the slot into the eye.

In the form of my invention which I have found best adapted to practical use I construct the guard of wire. In the drawings I have shown this form as an illustrative embodiment, reference being made thereto throughout specification and drawings by like numerals correspondingly used throughout.

Figure 1 is a plan view of the threading end of a shuttle equipped with my invention. Fig. 2 is a central longitudinal section of the parts shown in Fig. 1 and Fig. 3 is a view of the guard removed.

The shuttle body 1 may be of any usual construction having a bobbin chamber 2 in which is located the bobbin 3 on which is wound a thread T. From the forward end of the bobbin chamber 2 leads the eye 4 to which the threading slots 5 and 6 connect.

All this is usual and standard construction and only necessarily considered in connection with the guard which I will now describe. This guard consists of a bent top bar to which I shall refer generally as 10, 60 held in place by a forward, downwardly bent end 8 and a rear, downwardly bent end 9. These ends 8 and 9 serve to hold the bar 10 in proper position across the slot 5 being driven into the wood of the shuttle 65 body 1 to hold the bar in proper relation thereto. The bar 10 comprises a central portion 10¹ offset laterally from the straight line connecting its ends and also slightly raised above the levels of the portions 10² 70 and 10³ which connect the portion 10¹ with the end pins 8 and 9 respectively. The offset portion 10¹ is connected to the portions 10² and 10³ by inclined bends 10⁵ and 10⁴ respectively. The slot 5 is usually diagonally 75 disposed with regard to the longitudinal axis of the shuttle and in the form illustrated is sawed on a curve. The guard 10 is positioned transversely of this slot with its end 9 on one side and its end 8 on the other 80 side. The portions 10⁴ and 10² preferably cross the slot 5 at right angles so as to form the most effective bars to direct unthreading movement in the line of the slot. The portion 10³ is also preferably disposed at about 85 right angles to the eye 4 and substantially parallel with that portion of the slot 5 which enters the bobbin chamber 2.

At one side of the opening between the eye 4 and the chamber 2 a pin 11 is usually 90 driven for strengthening the tongue of wood formed in the shuttle body 1 by the two slots 5 and 6. This pin forms also a smooth guide and wear post over which the thread T runs when properly lodged in the eye 4. 95 In this position it is guided between this pin 11 and the vertical end 9. Any de-threading motion is therefore opposed by the part 9 or 10³ or if the thread should attempt to work forward in the slot 5 it would 100 meet the transversely disposed part 10⁴.

The portion 10¹ of the guard has been described as raised above the levels of the portions 10² and 10³. In the threading operation the thread T is passed above the bar 10¹ 105 (referring to the parts as disposed in Fig. 1) and drawn down so that, passing under the portions 10⁴, 10² and 10⁵ it enters the slot 5 at the edge of the shuttle and lands at the intersection of the slots 5 and 6. At this 110

moment it occupies a path indicated in dotted lines in Fig. 1 and running from the bobbin 3, beneath the bent portions 10⁴ and 10⁵ and over the portion 10² which traverses the 5 slot 5 thence into the slot 5 and down to the outer section of the slot 6. This is performed by the operative to the usual forward and slightly lateral movement of the hand. The next usual movement and the 10 one next made with my invention, is a rearward pull. Its effect is as follows: The slight backward movement of the hand causes the thread T, while being pulled through the slots 5 and 6 to travel back on 15 the bar 10² across which it is being drawn. This backward movement will land it instantly on the portion 10⁵ from which it successively slips to 10¹ thence to 10⁴ until it pulls past 10³. During this movement it 20 has been passing substantially, vertically down through the slot 5 and all the time slipping back toward the direct connection between the eye 4 and the bobbin chamber 2. As soon as it passes the portion 10³ it is 25 landed between the vertical part 9 and the pin 11 and at the same time its outer end is laid within the eye 4 through which it may feed.

Any unthreading tendency which may 30 originate within the bobbin chamber is met with the transversely disposed parts 9 or 10³ which absolutely bar the way.

Any move back from the opposite end of 35 the slot is squarely met by the transversely disposed part 10².

It will readily be seen that as far as the slot is concerned the thread is absolutely barred at either end from voluntary movement.

40 Various modifications in the bending of the guard, in the material and construction thereof, in the exact disposal of the same and generally in the details of form and arrangement may absolutely be made, all without departing from the spirit of my invention if within the limits of the appended 45 claims.

What I therefore claim and desire to secure by Letters Patent is:

50 1. In a shuttle of the class described, having a transverse delivery eye and a threading passage with an exposed upper edge and an oppositely extending underlying portion, a threading bar disposed across said exposed 55 edge and extending from the delivery side

of the receiving end of the threading passage at the rear of the delivery eye to the opposite side of said passage forward of said eye.

2. In a shuttle of the class described having a delivery eye and a threading passage leading thereto, a thread guide set transversely to the plane of entry of the thread into said passage and adapted to form a loop in said thread during said entry, said guide 60 65 having surfaces having a directive tendency toward said delivery eye.

3. A guard for the threading slot of a shuttle consisting of a bar, means for supporting it transversely of the slot, said bar 70 comprising a central bowed portion and substantially straight portions connecting the ends of said bar with said supporting means, said bowed portion being slightly tilted up.

4. In combination with a shuttle of the 75 class described, a guard for the threading slot, comprising an overlapping section having a rearwardly inclined guiding edge on one side and transversely disposed barring edges on the opposite side.

5. In combination with a shuttle of the class described a transverse guard for the threading slot thereof consisting of a bar having downturned ends lodged in the shuttle, said bar having a central bowed portion 80 85 overlying said slot in general parallelism therewith.

6. In a shuttle of the class described having a threaded slot a bar running from the throat at one side of the slot overlying a 90 portion of said slot between its ends, returning to the side of the slot first mentioned and again traversing said slot.

7. In a shuttle of the class described a guard for the threading slot comprising a 95 bar disposed transversely thereof adjacent to the shuttle edge and extending rearwardly adjacent to said slot.

8. In a shuttle of the class described having a threading slot, a thread guide disposed 100 across said slot but adjacent thereto and adapted to hold a loop of the thread during the passage of the thread through said slot.

In testimony whereof I affix my signature 105 in presence of two witnesses.

EUSEBE H. DAUDELIN.
